UNITED STATES PATENT OFFICE.

ROY W. MACKNEER, OF MOOREFIELD, WEST VIRGINIA.

SWING.

1,025,819.

Specification of Letters Patent.

Patented May 7, 1912.

Application filed April 15, 1911. Serial No. 621,292.

To all whom it may concern:

Be it known that I, ROY W. MACKNEER, a citizen of the United States, residing at Moorefield, in the county of Hardy and State of West Virginia, have invented new and useful Improvements in Swings, of which the following is a specification.

This invention relates to swings, the object of the invention being to provide in the construction of the swing an improved construction of reclining chair embodying relatively adjustable back and foot-rest-forming members and to provide means facilitating the adjustment of such members and for holding them securely in their adjusted positions.

In the drawings, forming a portion of this specification and in which like numerals of reference indicate similar parts in the several views:—Figure 1 is a side view of my improved swing. Fig. 2 is a rear view thereof. Fig. 3 is a section on line 3—3 of Fig. 1. Fig. 4 is a section on line 4—4 of Fig. 1. Fig. 5 is a section on line 5—5 of Fig. 1. Fig. 6 is a section on line 6—6 of Fig. 2. Fig. 7 is a view similar to Fig. 1 showing a slightly modified form of the invention.

My improved swing embodies a reclining chair 1 which comprises a slatted bottom 2 which is provided with depending side bars 3 which are suitably secured to the slats 4 and connected with each other by the retaining bolt 5. The chair is provided with arm rests 6 which are supported upon the sides 3 by rungs 7. Eye bolts 8 extend vertically through the side bars 3 and through the arm rests 6, the eyes 9 of which being attached to suitable suspending devices such as the chains 10 shown herein.

A back 11 is provided and it preferably includes side members 12 and the horizontal members 13 and 14. The members 13 and 14 are connected with each other by the rungs 15. A clamping bolt 16 extends through the member 14 and is suitably connected with the side members 12, as shown. The side members 12 extend downwardly below the member 14 and they are provided with detachable clamping bolts 17 which are designed for interchangeable engagement in the openings 18 in the bottom bars 19 of the chair. The side members 12 are hinged, as at 20, to the side members 3 at the rear ends thereof and through the provision of such hinges the chair back can be

adjusted so as to lie at any required or desired angle with respect to the chair bottom, the engagement of the clamping bolts 17 in the longitudinally arranged series of perforations 18 in the bottom members 19 serving to hold the back in its adjusted position. In addition to the means just described the side members 12 of the back are preferably formed to provide longitudinal slots 21. The arm rests 6 are provided with longitudinally adjustable links 22, the rear ends of the said links being provided with retaining bolts 23 which are adjustably mounted in the slots 21, as shown in Fig. 1 of the drawings. The links 22 are preferably provided with longitudinal slots 24 through which the clamping bolts 25 on the arm rests extend.

The bottom bars 19 are provided with vertically disposed brackets 26 which are connected with each other by a horizontally disposed rod 27. A foot-rest 28 is located in advance of the chair bottom and it preferably includes a supporting frame 29 having side bars 30 which are provided at their rear upper portion with a plate 31. The side bars 30 are grooved longitudinally and the longitudinal walls of the groove are spaced from the plate 31 so as to form therewith a longitudinal slot 32. The ends of the rod 27 extend into the slots 32 in the said side bars 30 so as to permit adjustment of the foot-rest with respect to the said rod.

With a view of holding the foot-rest in the desired adjusted position I preferably provide each bar 30 with a pivoted retaining device or keeper 33. As shown in the drawings, the ends of the rod 27 are removably fitted in recesses 34 in the upper ends of the brackets 26. The retaining or keeper plates 33 are each provided with a longitudinal series of recesses 35 which are designed to engage the rod 27 so as to hold the same positively against sliding movement in the slots 32. The rear ends of the retaining or keeper plates are detachably secured to the side bars 30 by means of fastening devices 36. The forward ends of the side bars 30 have secured thereto the forward extremities of adjusting chains 37. These chains extend rearwardly and their links are designed for interchangeable engagement with retaining devices 38 which are supported by the arm rests. The side bars 3 of the chair bottom and the bottom bars 19 are connected with each by relatively adjustable links 39

and 40. The links 40 are pivoted to the side bars 3, and as shown, they are slotted longitudinally to receive the clamping bolts 41 which extend from the links 39.

5 From the construction described it will be seen that the back of the chair may be adjusted at various angles with respect to the bottom of the chair. The foot-rest may be also adjusted at various angles with respect 10 to the bottom of the chair and with respect to the back thereof and its specific use in connection with the specific back described will afford to the user of the chair considerable comfort.

15 In the modified form of the invention shown in Fig. 7, the side members 12' are provided with clamping bolts 41 which extend through longitudinal slots 42 and the bottom bars 43 through longitudinal slots 20 44 in the foot rest bars 45. The brackets 46 are provided with vertical slots 47 which extend across the slots 44 in the foot rest bars. Clamping bolts 48 on the brackets extend through the vertical slots 47 and 25 through the slots 44, as shown.

I claim:

1. A chair comprising a bottom member, a back hingedly connected with the bottom, said back having side members provided 30 with longitudinal slots adjacent their upper ends, longitudinal adjustable link members carried by the arms of the chair, retaining bolts carried by the rear of the said links and adjustably mounted in the longitudinal 35 slots of the said side members of the back substantially as and for the purpose described.

2. A chair comprising a bottom member, a back hingedly connected with the bottom, 40 said back having side members extending below the bottom, the bottom having side members comprising relatively adjustable links, a horizontally adjustable bar connecting the side members of the bottom with the 45 said members of the back, and provided at

its rear end with a plurality of openings, and retaining bolts extending through the said slots of the side members of the back and adapted for interchangeable engagement with the said openings substantially 50 as and for the purpose described.

3. A chair comprising a bottom, a back hingedly connected with the bottom, said back having side members extending below the bottom, said bottom having side members pivoted thereto, a horizontally adjustable bar operatively connecting the side members, vertically disposed brackets supported by the said horizontally adjustable bars, a transversely disposed rod connecting 60 said brackets, a foot rest located forward of the bottom, a frame supporting said foot rest and adjustably supported by said transverse rod, and means on the frame for engaging the said rod to hold the said frame 65 in its adjusted position.

4. A chair comprising a bottom, a back hingedly mounted thereon having side bars extending below the back, side members located beneath the bottom and adjustably 70 supported thereby, an adjustable bar connecting the side members of the bottom with the side members of the back, a vertically disposed bracket supported by the said bar, a rod connecting the brackets and supported thereby, a foot rest, an adjustable frame supporting said foot rest and comprising a pair of side bars, said bars having longitudinal grooves therein, a plate covering the grooves to provide a slot adapted 75 for the reception of the said rod, and a retaining plate pivoted to the frame and adapted to engage the said rod to hold the said frame in its adjusted position.

In testimony whereof I affix my signature 80 in presence of two witnesses.

ROY W. MACKNEER.
